(57) CLAIM

The ornamental design for a shower head, as shown and described.

DESCRIPTION

1.1 is a perspective view of a shower head, showing my new design;

1.2 is a side view thereof;

1.3 is an end view thereof;

1.4 is a bottom view thereof; and

1.5 is a top view thereof.

The broken lines shown in views 1.1 through 1.4 are for the purpose of illustrating portions of the shower head that form no part of the claimed design.
